UNITED STATES PATENT OFFICE.

JESSE B. MARSHALL, OF MEDINA, OHIO.

CRIB STRUCTURE.

No. 926,707.

Specification of Letters Patent.

Patented June 29, 1909.

Application filed July 24, 1908. Serial No. 445,129.

To all whom it may concern:

Be it known that I, JESSE B. MARSHALL, a citizen of the United States, residing at Medina, in the county of Medina and State 5 of Ohio, have invented a new and useful Crib Structure, of which the following is a specification.

My invention relates to sheet metal structures for corn-cribs and the-like. Its object 10 is to provide a strong, durable, fireproof and comparatively inexpensive crib adapted to secure more perfect ventilation and readiness of access, together with absolute freedom from dampness and from the invasion of rodents.

15 It consists mainly of embedding in a cement or concrete base upon a suitable foundation, a sheet metal bottom to which is therein secured a series of sheet metal plates, preferably perforated throughout, solidly 20 united at their respective contiguous longitudinal edges to form a crib chamber; said structure provided with a suitable cover, and a ventilator shaft extending into the chamber and having perforations to permit free 25 circulation of air within said chamber.

My invention is illustrated by the accompanying drawings in which—

Figure 1 is a plan view of my metal crib with parts cut away to exhibit the interior. 30 Fig. 2 is a vertical longitudinal section of same on the line X—Y. Fig. 3 is a detail view of the means I use to form the sheet metal joints in its present embodiment. Fig. 4 is a detail cross section of the lower 35 part of one side of my crib structure, showing means of uniting the walls to the base and parts adjacent.

Referring to the drawings, 1 represents the vertical sheet metal plates, which being 40 solidly united edgewise, constitute the body or chamber of the crib. I preferably unite these adjacent longitudinal edges by constructing a flanged margin 10 on the same, and binding both flanges together by means 45 of a superposed metal strip 11 bent in form of a saddle, and secured by bolts or rivets a, as shown in Fig. 3. This superposed strip may however be omitted, or other means employed to securely unite said edges.

50 As the best means for covering the structure I form a sloping roof made up by the solid junction of a series of triangular sheet metal plates 2, 2 which are secured together in the same manner above described, and may 55 be of any desired slope or pitch. For the purpose of better ventilation, in corn cribs

especially, I punch the several vertical sheet metal plates with numerous perforations as shown, and construct a ventilator shaft 3, preferably also of sheet metal, and extend 60 the same downwardly into and through the crib chamber, and secure it at its lower end solidly in the concrete foundation to give it stability, and perforate it throughout its entire length to adapt it to afford the freest 65 possible ventilation of all parts of the chamber, and means for drying the contents thereof, which may thus be disposed all around said ventilator shaft.

A sub-foundation 6 for my crib should 70 usually be constructed in a manner suited to the situation and character of the soil, but in general, it is sufficient to lay a course of loose stones or coarse gravel to a point below the frost line. Upon the foundation I construct 75 a base 5 of concrete or cement, on which I first spread a thin layer to make the foundation level and even, and lay thereon a sheet metal bottom 7 to reinforce the concrete base, prevent dampness from arising within 80 the crib, and afford means for attaching the vertical sheet metal plates 1 which rest thereon, and then add a layer of concrete several inches in thickness all over this sheet metal bottom, and extend the layer beyond 85 the side plates (which are thus embedded therein at their lower ends) sufficiently to form a neat base 5 all around the crib bottom as shown in Fig. 1. The lower edges of said 90 vertical sheet metal plates may be solidly attached to said sheet metal bottom by means of bolts, angle irons, or any other suitable fastenings sufficient for the purpose, the said junction being reinforced by the weight of the structure walls and the concrete 95 environment aforesaid. This construction also gives solidity to the crib, and makes it water and damp proof.

As a preferred means for solidly uniting the lower edges of the walls 1, to the bottom 100 sheet metal plate 7, I use a flanged strip or angle iron c, and bolts d, locating the same either within or without the wall, and within the concrete layers 5 as shown in Fig. 4. I also provide a suitable opening 9, preferably in the roof, with a removable cover to facilitate the dumping of corn and other substances into the crib, and also construct a suitable door 4 at one side in front of an interior barrier in the usual well known way to 105 prevent free escape of the material within when the door is opened.

I am aware it is not new to construct a crib of perforated sheet metal sections and provide ventilating means therefor, and such I do not claim broadly. My improvement lies in the novel method of constructing a concrete floor for such cribs, in combination with improved means for securing the ventilator in position at the crib bottom, and the crib walls to the concrete floor, simplifying the construction and strengthening its parts, and making the crib more impervious to dampness, and more enduring and impene-
trable, and other and different openings to the crib may be made if desired, but

Having thus fully described my invention, what I claim as new and desire to secure by Letters Patent is;

1. In a crib structure, the combination with sheet metal walls, of a concrete floor, comprising a sub-foundation overlaid with concrete, a sheet metal plate embedded therein, and a layer of concrete extending over said metal plate beyond the walls, said walls being endwise secured by suitable fastenings to said metal plate; a base or margin of concrete around the bottom of said structure in connection with said floor, and a ventilator depending through said crib and endwise secured in said floor, substantially as set forth and for the purpose specified.

2. In a crib structure, the combination

with perforated sheet metal walls, of a concrete floor, comprising a sub-foundation overlaid with concrete, a sheet metal plate embedded therein, and a layer of concrete ex-
tending over said metal plate to said walls, said walls being endwise secured by suitable fastenings to said metal plate and concrete; a base or margin of concrete around the bottom of said structure in connection with said floor, and a ventilator shaft perforated from end to end, depending through said crib and endwise secured in said floor, substantially as set forth and for the purpose specified.

3. In a crib structure, the combination with a concrete floor comprising a sub-foun-
dation overlaid with concrete, a sheet metal plate embedded therein, and a layer of con-
crete extending over said plate; of a series of solidly united and perforated sheet metal plates endwise secured by suitable fastenings to said embedded plate; a concrete base or margin connected to said floor around the bottom of said structure, and a perforated ventilator depending through said crib verti-
cally, and endwise secured in said floor, sub-
stantially as set forth.

In witness whereof I hereunto set my hand.
JESSE B. MARSHALL.
